UNITED STATES PATENT OFFICE.

FRED H. DANIELS, OF WORCESTER, MASSACHUSETTS.

STEAM-ENGINE CONDENSER SYSTEM.

No. 853,772.

Specification of Letters Patent.

Patented May 14, 1907.

Application filed April 27, 1906. Serial No. 313,971.

To all whom it may concern:

Be it known that I, FRED H. DANIELS, of Worcester, Worcester county, Massachusetts, have invented a new and useful Improvement in Steam-Engine Condenser Systems, of which the following is a full, clear, and exact description, reference being had to the accompanying drawings, forming part of this specification, in which—

10 Figure 1 is a plan view, largely diagrammatic, of a steam engine and its vacuum pump and condenser, embodying my invention; Fig. 2 is a side elevation of the same; and Fig. 3 is an enlarged elevation of the 15 valve mechanism.

My invention has relation to steam engines of the condensing type, and more particularly to reversing engines. These engines run intermittently, being operated rapidly in one direction for a period of time, and then reversed to run rapidly in the other direction, or they may stop and stand idle for a number of minutes. Heretofore it has been customary to operate the condensers which condense the steam from this type of engine continuously, which involves the expense of continuously pumping the water supplied thereto. The present invention is designed to obviate this needless continuous operation of the condenser, and it consists in providing means whereby the power supply of the engine and of the condenser pump are simultaneously controlled, so that the condensing apparatus is started and stopped with the engine, and is, furthermore, operated at all times relatively to the operation of the engine.

My invention also consists in the novel construction, arrangement and combination 4c of parts, all substantially as hereinafter described and pointed out in the appended claims.

In the drawings, 2 designates a steam engine of any suitable type, 3 is the main steam supply pipe therefor, in which is located the main throttle or governing valve 4, operated by throttle lever 5 connected to its stem in the usual manner. 6 designates a condenser and vacuum pump, which may also be of any suitable character, and which receives the exhaust steam from the engine 2 through the exhaust pipe 7. The vacuum pump receives its steam supply through a pipe 8, which is shown as being a branch of the pipe 3, being connected thereto above the throttle valve 4. The pipe 8 is provided with a governing

valve 9, of any suitable character, such as a butterfly valve, and its stem is provided with a lever arm 10 which is connected by a link 11 with a lever arm 12 on the stem of the throttle valve 4.

13 is a by-pass pipe leading around the governing valve 9 of the steam supply pipe 8. This pipe is also provided with a valve 14.

By the arrangement described, it will be 65 readily seen that the movement of the throttle lever 5 to operate the main throttle valve 4 also effects a corresponding operation of the governor valve 8 controlling the supply to the vacuum pump. When the throttle 70 valve 4 of the main engine is closed, the valve 9 is also closed. The valves 4 and 8 are also arranged to synchronize with each other so that the amount of opening for the supply of steam to the vacuum pump is directly proportionate to the amount of opening of the main throttle valve. The speed of the vacuum pump is, therefore, at all times such as to insure the condensation of whatever amount of steam is exhausted from the 80 main engine. The by-pass pipe 13 and its valve 14 are provided in order that when the main engine throttle valve is closed, a small amount of steam may nevertheless be supplied to the vacuum pump in order to hold 85 the vacuum in the exhaust pipe and to condense the small quantity of steam which passes through the main engine by leakage, etc. This by-pass can be cut out by closing the valve 14, or any desired speed of the vacuum pump can be maintained by the adjustment of this valve, independently of the valve 9, when desired.

The advantages of my invention result from the increased economy in operation due 95 to the ability to control the operation of the condenser relatively to the operation of the engine, and from the simplicity and convenience of operation of the means provided for securing this result.

As above indicated, my invention is applicable to various types of engines and condensers, and various changes may be made in the arrangement and connection of the valves without departing from the spirit and scope 105 of my invention.

What I claim is:—

1. A steam engine having a condenser engine, and means for governing the speed of the condenser engine in proportion to the speed of the engine, substantially as described.
2. A steam engine having a condenser en-

gine, and means for governing the supply of live steam to the condenser engine in proportion to the supply of live steam to the main engine, substantially as described.

5 3. A steam engine having a condenser engine, and means for governing the speed of the condenser engine by and in proportion to the speed of the engine, substantially as described.

10 4. A steam engine having a condenser engine, steam supply pipes for the main engine and the condenser engine, and means common to the two steam pipes for simultaneously and proportionately controlling the supply of live steam to the main engine and the condenser engine, substantially as described.

15 5. The combination of a steam engine, a condenser therefor, a supply-pump for the condenser, and means for automatically controlling the speed of the pump simultaneously with that of the engine; substantially as described.

20 6. The combination of a steam engine, a condenser therefor, a pump for supplying the condenser, an engine for operating the pump, valves for controlling the supply of live steam to the engines, and means for synchronizing the operations of said valves; substantially as described.

25 30 7. The combination of a steam engine, a condenser, a pump for supplying the condenser, and connected valve mechanism for simultaneously controlling the live steam

supply of the engine and pump; substantially as described.

8. In a steam engine, a main throttle or governing valve for controlling the steam supply thereto, a steam pump for operating the engine condenser, a valve for controlling the supply of steam to said pump, and means for simultaneously operating the said valves; substantially as described.

9. A steam engine having a main throttle valve, a condenser for the engine, a steam pump for supplying water to the condenser, a controlling valve for the steam supply of said pump, means for operating said valves in unison, and means for regulating the steam supply to the pump independently of the said valves; substantially as described.

10. A steam engine having a main throttle valve, a condenser for the engine, a steam pump for supplying the condenser, a main valve for controlling the steam supply to the pump, means for operating said valves in unison, and a valved by-pass around the last named valve and affording independent means for controlling the steam supply of the pump; substantially as described.

In testimony whereof, I have hereunto set my hand.

FRED H. DANIELS.
